UNITED STATES PATENT OFFICE

GEORGE ERNEST NAGEL, OF COLUMBUS, OHIO

RAILWAY CROSSING

Application filed June 19, 1930. Serial No. 462,335.

This invention relates to railway crossings and has for its object to provide, in a manner as hereinafter set forth, a crossing of the class referred to including courses of composite, armored slabs and means associated with the slabs of the courses to prevent the slabs from heaving or becoming dislocated.

A further object of the invention is to provide, in a manner as hereinafter set forth, a railroad crossing including courses of composite, armored slabs and interengaging interlocking means at the opposed ends of the slabs of each course for holding the slabs down, and with said means so constructed and arranged to prevent the corroding thereof whereby the crossing can be readily removed for track maintenance when desired.

A further object of the invention is to provide, in a manner as hereinafter set forth, a composite, armored slab for railway crossings and with the slab including a concrete body and a metallic plate extending entirely over the upper face of the body and turned down at its edges, and with the plate having inherent parts thereof extended downwardly and embedded in the concrete body, and by this arrangement there is provided a wearing surface at the entire top of the slab, but further there will be developed a beam strength in the slab which is equal or superior to reinforcing bars for the concrete body.

A further object of the invention is to provide, in a manner as hereinafter set forth, a composite, armored slab for railway crossings so formed that it is capable of being used to pave diagonal crossings and fill in around the crossing frogs, diamonds, etc.

A further object of the invention is to provide, in a manner as hereinafter set forth, a composite, armored slab for railway crossings and with the slab including a concrete body and a metallic reinforcing or armoring plate, the concrete body being the under support for the plate. The slab is capable of being used to pave diagonal crossings and fill in around the crossing frogs, diamonds, etc., by simply cutting the plate upon diagonal lines and to conform the concrete body to the shape of the plate. In the case of all metal crossings the cost of an under support of

steel in such special shapes is extremely high, whereby by setting up a crossing slab in the manner as referred to, it is materially less expensive than setting up the slab with an under support of steel in a special shape. 55

Further objects of the invention are to provide, in a manner as hereinafter set forth, a railway crossing which is simple in its construction and arrangement, strong, durable, compact, expeditiously removed when occasion requires, thoroughly efficient in its use, readily installed and comparatively inexpensive to manufacture. 60

With the foregoing and other objects in view the invention consists of the novel construction, combination and arrangement of parts as hereinafter more specifically described, and illustrated in the accompanying drawings, wherein is shown an embodiment 65 of the invention, but it is to be understood that changes, variations and modifications can be resorted to which fall within the scope 70 of the claims hereunto appended.

In the drawings wherein like reference characters denote corresponding parts throughout the several views:— 75

Figure 1 is a fragmentary view in top plan of a railway crossing in accordance with this invention.

Figure 2 is a section on line 2—2, Figure 1. 80

Figure 3 is a transverse sectional view of a railway crossing in accordance with this invention as applied to a track.

Figure 4 is a fragmentary view in top plan of an armor plate forming an element of the 85 slab.

Figure 5 is a section on line 5—5, Figure 4.

Figure 6 is a section on line 6—6, Figure 4.

A railway crossing in accordance with this invention will be set up of courses of composite, armored slabs. A set of sidewise opposed abutting courses will be positioned between the pair of track rails upon the supporting ties for the latter and an outer course positioned exteriorly of each track rail upon the projecting ends of the rail ties or sleepers. The end slabs of each course will be slightly different in form with respect to the intermediate slab or slabs of the courses. Figure 1 illustrates one end slab and one interme- 90 95 100

diate slab of a course and which are indicated generally at 1, 2 respectively. The slabs of each course are arranged in endwise opposed, abutting relation. The drawings illustrate 5 by way of example, longitudinally disposed courses of slabs, or rather courses disposed lengthwise with respect to the track. The outer courses of the set of courses are arranged in sidewise opposed abutting relation 10 with respect to the sides of the intermediate course or courses of said set. When a plurality of intermediate courses form part of the set they are arranged in sidewise opposed abutting relation. The drawings illustrate 15 by way of example, the set of courses as consisting of a pair of outer courses and one intermediate course. Each slab is armored by a steel plate extending throughout the upper surface of the body portion of the slab. The body portion of the slab is constructed of concrete. The plate which armors the slab can be smooth throughout its upper face or roughened or corrugated or provided with spaced, upstanding protuberances and fur- 20 ther having inherent parts thereof for anchoring it to the concrete body. The courses of the set of courses are designated A, B and C and the pair of outer courses at D and E.

The spaced ties or sleepers of a railway 30 track are indicated at 3 and the track rails at 4, 5. The rails 4, 5 are secured to the ties 3 by the spikes 6. The ties project laterally from the rails 4, 5 as at 4', 5', and upon the former are mounted courses D and upon the latter courses E. Flangeways 7, 8 are positioned against the inner sides of the rails 4, 5 respectively. Filler members 9, 10 are positioned against the outer sides of the track rails 4, 5 respectively. The flangeways and 35 fillers extend lengthwise of the track rails and are preferably constructed of oak. Each flangeway is formed with a set of spaced sockets 11 which open at the inner side thereof. Each filler is formed with a 40 set of spaced sockets 12 which open at the outer sides of the filler. The rails 4, 5 are mounted on chair plates 13. The courses D and E oppose the filling members 9, 10 respectively. The courses A, C oppose the 45 flangeways 7, 8 respectively.

The number of the slabs of each of the courses will correspond and the end slabs 1 of each course comprise a concrete body 14 having its upper surface at its outer end bevelled downwardly to the free edge of such end as at 15. Each end slab 1 of each course is formed with a plurality of spaced, V-shaped notches 16 for the passage of spikes 17 to secure the slabs to the ties or sleepers 3. 50 The spikes 17 also act to prevent the longitudinal shifting of the courses with respect to the ties or sleepers 3.

Each end slab 1 of each course has its concrete body armored by a metallic plate 18 55 which completely covers the upper surface

of the concrete body and is formed with downturned flanges 19 at its sides and ends. The flanges have the edges thereof seated against shoulders 20, 20' formed respectively on the sides and ends of the concrete body. The shoulders 20, 20' are arranged above the center of the sides and edges of the concrete body. The inner faces of the body of the plate 18 and flanges is snugly engaged throughout by the concrete body. The outer faces of the flanges 19 are flush with the side and end faces of the concrete body below the shoulders 20.

The end slabs 1 of the courses A, B and C have each side thereof, below shoulder 20 provided with spaced sockets 21 which register with certain of the sockets 11 and mounted in said registering sockets are dowel pins 22 for connecting said slabs to the flangeways 7, 8.

Each end slab 1 of each of the courses has its inner end, below the inner end shoulder 20 provided with spaced sockets 23 for a purpose to be presently referred to.

Each intermediate slab 2 of each course 30 comprises a concrete body 24 which is armored throughout its upper face by a metallic plate 25 having downturned flanges 26 at its sides and ends which seat upon shoulders 27 formed on the side and end faces of the body 24 below the top of the latter. Each slab 2 has each of its ends provided with spaced sockets as at 28, 29. If each course is formed with but one slab 2 the sockets 28 register with the sockets 23 of one end slab 190 and the sockets 29 with the sockets 23 of the other end slab. If each course is formed with two or more slabs 2, the sockets 28, 29 of a slab 2 will register with sockets 28, 29 of an adjacent slab or slabs 2 and with the 195 sockets 23 of slabs 1. Dowel pins 30 are mounted in the registering sockets for coupling the slabs together.

The intermediate slab or slabs 2 of the courses A and B have their outer side faces 110 provided with spaced sockets 31 registering with certain of the sockets 11 and mounted in registering sockets 11, 31 are dowel pins 32 for connecting slabs 2 of courses A and B to the flangeways 7, 8. The sockets 28, 29 and 115 31 are arranged below the flanges 26.

The inner side of each of the slabs 1, 2 of the courses D and E, below the inner side flanges of the armoring plates is formed with spaced sockets 32 which register with the 120 sockets 12. Mounted in the registering sockets 12, 32 are dowel pins 33 for connecting the slabs of courses D and E to the filler members 9, 10.

The dowel pins hold the slabs down and prevent them from heaving or becoming dislocated. Further by such arrangement the crossing can be readily removed for track maintenance when desired.

When the slabs of the courses A, B and C 125

are in position certain of the concrete body portions abut each other and abut the flangeways and certain of the flanges abut each other and the flangeways.

5 When the slabs of the courses D and E are in position the concrete body portions and certain of the flanges thereof abut each other and the concrete body portions and certain of the inner side flanges abut the filler members.

Preferably the armoring plate forming an element of each slab will be provided with anchoring means therefor, and such means will be inherent parts of the plate. Preferably the armoring plate will be formed with upstanding protuberances.

The preferred form of armoring plate is as illustrated in Figures 4, 5 and 6. The body of the plate is indicated at 35 and the flanges at 37. The body 35 is formed with lengthwise rows of spaced, tapered, hollow protuberances 38 having flattened tops 39. The length of the protuberances is materially greater than the width thereof. The protuberances of one row are staggered with respect to the protuberances of an adjacent row. The flat tops of the protuberances provide tread surfaces. The body 35 is further formed with depending tongues 40 providing inherent anchoring means for the plate. The tongues 40 are arranged in staggered relation with respect to each other. The tongues are positioned between pairs of protuberances 38 of the several rows. The tongues are provided by slitting the body 35 and bending inwardly the material freed by the slit. Each tongue gradually decreases in width from its point of joinder with the body 35 to its free end. Each tongue is of slightly greater length than a protuberance, and is formed with a flat, elongated intermediate portion 41, an inclined end portion 42 and an end portion 43 formed of rearwardly directed inclined part 44 which terminates in a vertical part 45 disposed in a plane rearwardly of and in spaced relation to the plane of portion 41. The part 44 merges into the portion 41. The portion 42 and part 45 incline in opposite directions, the former toward the point of joinder of the tongue body 35 and the latter toward the part 44. The part 44 is positioned substantially in alignment with the point of joinder of the tongue with body 35. The shape of the tongue provides for the anchoring thereof in the concrete body portion or under support for the plate. Preferably the slabs are of a height slightly less than the height of the track rails.

The upper corners of each of the armoring plates are rounded. The tongues not only anchor the plates to the concrete body portion or under support for the plates, but also act as a reinforcing means for such body. As the plates completely envelope the upper part of the concrete body the life of the lat-

ter is materially enhanced. As the tongues are arranged staggered with respect to each other they are anchored at spaced points to the concrete body.

What I claim is:—

1. A railroad crossing comprising a set of courses of armored, endwise opposed slabs adapted for interposition between a pair of track rails, a single course of armored slabs adapted to be positioned exteriorly of each of said rails, interengaging, interlocking means for connecting the opposed ends of the slabs of each course together, said means arranged below the top of said slabs, means interengaging in the outer sides of the outer slabs of the outer courses of said set of courses for connecting such slabs to flangeways positioned against the track rails, and means interengaging in the inner sides of the slabs of said single courses for connecting such slabs to filler members positioned against said track rails.

2. A railroad crossing comprising a set of courses of armored, endwise opposed slabs adapted for interposition between a pair of track rails, a single course of armored slabs adapted to be positioned exteriorly of each of said rails, interengaging, interlocking means for connecting the opposed ends of the slabs of each course together, said means arranged below the top of said slabs, means interengaging in the outer sides of the outer slabs of the outer courses of said set of courses for connecting such slabs to flangeways positioned against the track rails, and means interengaging in the inner sides of the slabs of said single courses for connecting such slabs to filler members positioned against said track rails, each of said slabs including a concrete under support having its upper portion encompassed by a metallic armoring plate, each end slab of each of said courses having a bevelled outer end provided with notches for the passage of holdfast devices.

3. In railroad crossings, a slab formed of a concrete under support and an armoring plate formed with side and end depending flanges, the flanges being of less height than said body, said plate encompassing the upper portion of said support and with the outer faces of said flanges flush with the side and end faces of said support.

4. In railroad crossings, a slab formed of a concrete under support and an armoring plate formed with side and end depending flanges, the flanges being of less height than said body, said plate encompassing the upper portion of said support and with the outer faces of said flanges flush with the side and end faces of said support, said support having its inner end formed with spaced sockets below the inner end flange of said plate.

5. In railroad crossings, a slab formed of a concrete under support and an armoring plate formed with side and end depending

flanges, the flanges being of less height than said body, said plate encompassing the upper portion of said support and with the outer faces of said flanges flush with the side and end faces of said support, said support having its inner end formed with spaced sockets below the inner end flange of said plate, and its outer side below the outer side flange of the plate provided with a series of spaced sockets.

6. In railroad crossings, an armored slab formed of a concrete under support and a metallic plate having depending flanges opposing the upper portion of the support, said slab provided at one side and at one end with spaced dowel pin receiving sockets.

7. In railroad crossings, an armored slab formed of a concrete under support and a metallic plate having depending flanges opposing the upper portion of the support, said slab provided at one side and at one end with spaced dowel pin receiving sockets and at its outer end with spaced notches.

8. In railroad crossings, an armored slab formed of a concrete under support and a metallic plate having depending flanges opposing the upper portion of the support, said slab provided at one side thereof with spaced dowel pin receiving sockets.

9. In railroad crossings, an armored slab formed of a concrete under support and a metallic plate having depending flanges opposing the upper portion of the support, said slab provided at each end with spaced dowel pin receiving sockets, said plate having inherent parts thereof depending therefrom to provide tongues embedded in said support for anchoring the plate to the latter.

10. In railroad crossings, an armored slab formed of a concrete under support and a metallic plate encompassing the upper portion of the support, said slab provided at one side and at one end with spaced dowel pin receiving sockets, said plate having inherent parts thereof depending therefrom to provide tongues embedded in said support for anchoring the plate to the latter.

11. In railroad crossings, an armored slab formed of a concrete under support and a metallic plate encompassing the upper portion of the support, said slab provided at one side and at one end with spaced dowel pin receiving sockets and at its outer end with spaced notches, said plate having inherent parts thereof depending therefrom to provide tongues embedded in said support for anchoring the plate to the latter.

12. In railroad crossings, an armored slab formed of a concrete under support and a metallic plate encompassing the upper portion of the support, said slab provided at one side thereof with spaced dowel pin receiving sockets, said plate having inherent parts thereof depending therefrom to provide

tongues embedded in said support for anchoring the plate to the latter.

13. In railroad crossings, an armored slab formed of a concrete under support and a metallic plate encompassing the upper portion of the support, said slab provided at each end with spaced dowel pin receiving sockets, said plate having inherent parts thereof depending therefrom to provide tongues embedded in said support for anchoring the plate to the latter, said plate further including upstanding, spaced protuberances, said tongues having portions disposed at angles with respect to each other.

14. In railroad crossings, an armored slab formed of a concrete under support and a metallic plate encompassing the upper portion of the support, said slab provided at one side and at one end with spaced dowel pin receiving sockets, said plate having inherent parts thereof depending therefrom to provide tongues embedded in said support for anchoring the plate to the latter, said plate further including upstanding, spaced protuberances, said tongues having portions disposed at angles with respect to each other.

15. In railroad crossings, an armored slab formed of a concrete under support and a metallic plate encompassing the upper portion of the support, said slab provided at one side and at one end with spaced dowel pin receiving sockets and at its outer end with spaced notches, said plate having inherent parts thereof depending therefrom to provide tongues embedded in said support for anchoring the plate to the latter, said plate further including upstanding, spaced protuberances, said tongues having portions disposed at angles with respect to each other.

16. In railroad crossings, an armored slab formed of a concrete under support and a metallic plate encompassing the upper portion of the support, said slab provided at one side thereof with spaced dowel pin receiving sockets, said plate having inherent parts thereof depending therefrom to provide tongues embedded in said support for anchoring the plate to the latter, said plate further including upstanding, spaced protuberances, said tongues having portions disposed at angles with respect to each other.

17. In railroad crossings, an armored slab formed of a concrete under support and a metallic plate encompassing the upper portion of the support, said slab provided with sockets below its upper face, said plate having inherent parts arranged in staggered relation with respect to each other embedded in said support and providing anchoring means for the plate.

18. In railroad crossings, an armored slab formed of a concrete under support and a metallic plate encompassing the upper portion of the support, said slab provided with sockets below its upper face, said plate hav-

ing inherent parts arranged in staggered relation with respect to each other embedded in said support and providing anchoring means for the plate, each of said tongues including parts disposed at an angle to each other.

In testimony whereof, I affix my signature hereto.

GEORGE ERNEST NAGEL.
